Attorney

UNITED STATES PATENT OFFICE.

JOSEPH POSA, OF BRIDGEPORT, CONNECTICUT.

MOUTH APPLIANCE.

Application filed September 9, 1921. Serial No. 499,520.

To all whom it may concern:

Be it known that I, JOSEPH POSA, a subject of Hungary, and residing at the city of Bridgeport, in the county of Fairfield and State of Connecticut, U. S. A., have invented certain new and useful Improvements in Mouth Appliances; and I do declare the following to be a full, clear, and exact description of the invention, such as will enable others skilled in the art to which it applies to make and use the same.

This invention relates to certain new and useful improvements in mouth appliances and more particularly relates to an appliance which is placed in the mouth and which is used to support or hold the cheeks in an outward direction so as to cause same to have a normal or plump appearance.

At the present time there are great many persons who have what are commonly termed sunken cheeks and the present invention therefore aims to provide means, which is worn in the mouth of the person so afflicted and which forces or holds the cheeks so that the latter are possessed of a normal appearance.

The invention further aims to provide a device of this type which is of simple and economical construction, and which can be easily and quickly applied and removed and which is comfortable to the user.

In the drawings:

Figure 1, is a front elevation of the device in operative position;

Figure 2 is a top plan view; and

Figure 3, is a detail end elevation.

In proceeding in accordance with the present invention, a pair of approximately ovaloid cheek-engaging members 1 are provided which are secured to the respective ends of a connecting bar or support 2. The support is curved as illustrated in the drawings, and presents a somewhat U-shaped formation, with the result that the cheek-engaging members 1, are held in approximate parallelism. The U-shaped support or bar 2 may be made of any suitable material, such as rubber, celluloid or even wire, so as to be possessed of a certain amount of resiliency. The ends of the bar 2 are connected in any suitable manner to members 1 at the juncture of the forward or front sides and the bottoms of the members 1, so that the latter have an upstanding relation to the bar, as illustrated in the drawings. The par-

ticular connection here shown consists of having the ends of the bar flattened and sharpened for being embedded in or being driven into the material of members 1. The cheeks engaging members 1 may be formed of any suitable material, such as celluloid rubber or light metal, as aluminum, and are curved or rounded on their outer sides, so as to engage the inner sides of the cheeks and impart a natural rounded conformation to the same.

The bar or support 2 is in use arranged to lie between the inside of the upper lip and the front of the upper gum or jaw of the user, in which position, it is held by the natural pressure of the upper lip against the upper gum or jaw. The cheek engaging members are also arranged so as to lie at their upper portions between the sides of the upper gum or jaw and to engage against the insides of the cheeks and are also held by the pressure of the cheeks against the upper jaw or at the sides of the latter. The cheeks moreover, due to their unnatural sunken condition, will press against the pads or members 1, and since each cheek exerts pressure against the members 1 and in opposite directions or towards each other, it will be seen that the tendency will be to hold the device in the position illustrated in the drawings.

What is claimed is:

1. In a device of the type set forth, an approximately U-shaped bar formed to be arranged between the inside of the upper lip and the outer side of the upper jaw of the user, and a pair of approximately ovaloid pad-like members mounted on the ends of the bar and arranged to engage the insides of the cheeks of the user so as to hold the latter in normal outward position.

2. In a device of the type set forth, a pair of members formed to engage the inside of the cheeks of the user, and a flat resilient bowed strip on whose extremities said members are mounted, said strip being applied between the inside of the upper lip and the outer side of the upper jaw of the user and secured in this position by resilient clamping of said members against the rear portions of the upper jaw.

In testimony whereof I affix my signature hereto.

JOSEPH POSA.
